[57] CLAIM

The ornamental design for a motorcycle mirror, as shown and described.

DESCRIPTION

FIG. 1 is a front view of the motorcycle mirror;

FIG. 2 is a back view thereof;

FIG. 3 is a right view thereof;

FIG. 4 is a left view thereof;

FIG. 5 is a top view thereof; and,

FIG. 6 is a bottom view thereof.

The broken line showing of an indicator light on the attachment arm in FIGS. 1 and 2 and of grooves on the back of the mirror in FIG. 2 and on the mirror sides, FIGS. 3 through 6, are for illustrative purposes only and form no part of the claimed design.
